ABSTRACT OF THE DISCLOSURE

The present device includes a conveyor operable to advance a jig table carrying the wooden elements forming a truss through a press. The spaced joints of the truss are successively located below a press platen whereat nail plates of the type having a plurality of teeth struck therefrom are embedded into the joints. A fluid actuated slave cylinder is located adjacent the leading heel reaction pad of the jig table and is operably connected to a pivoted member located below the leading heel joint of the truss whereby actuation of the slave cylinder pivots the member upwardly to elevate the leading portion of the truss from the jig table. A master cylinder is mounted on the jig table behind and connected to the slave cylinder via a fluid line. The master cylinder carries a linkage projecting above the truss elements whereby the linkage actuates the master cylinder in response to downward movement of the press platen to provide fluid to the slave cylinder, thereby elevating the leading heel portion of the completed truss above the jig table onto an automated truss unloading mechanism.

BACKGROUND AND SUMMARY OF THE PRESENT INVENTION

The present invention relates to automatic machinery for producing wooden structural elements and more particularly to apparatus which aids in the unloading of completed wooden structures, such as roof trusses, from the automatic machinery by which the structures are produced.

Recently, the wooden building construction industry has shown a marked trend toward prefabrication of wooden structural components, particularly in the construction of relatively low cost housing. The most common prefabricated element of the various portions of houses which have been preassembled in this fashion is probably the monoplane roof truss.

Concurrently with this development, prefabrication techniques and practices in forming prefabricated wooden structures, such as roof trusses, have evolved from joint formation by hand nailing and bolting techniques to the improved and far superior mode of construction which was made possible by the advent of structural butt joints employing unitary connector plates of the type described in U.S. Pat. No. 2,877,520 of common ownership herewith. A current method of producing prefabricated roof trusses employing the joint construction of the foregoing patent employs a jig assembly, an example of which is disclosed in U.S. Pat. No. 3,241,585 of common ownership herewith. These developments have made it possible to manufacture trusses of various sizes and shapes with a minimum of skilled labor and at substantially reduced cost. However, since completed trusses are of substantial weight, bulky and somewhat awkward to remove from the jig assembly, it has been a problem to offload the trusses from the jig assemblies with a minimum of labor onto appropriate storage or transportation facilities.

Automated truss unloading and stacking devices have

2

been provided in the past for removing the completed truss from the jig assembly and positioning it in an upright position for subsequent handling. An example of such devices is disclosed in copending application Ser. No. 578,365, filed Sept. 9, 1966, now Pat. No. 3,389,812, of common ownership herewith. Such devices are located at the output side of a press and automatically remove the truss from the jig by virtually peeling the completed truss from the jig assembly. Elevation of the leading portion of the truss is, however, necessary to initially locate the truss in an offloading position relative to the unloading and stacking devices.

According to the present invention, it has been found that the truss can be automatically elevated from the jig assembly prior to its engagement on the unloading device by an assembly carried by the jig table. Moreover, the leading heel portion of the completed truss can be elevated from the jig table to an unloading position at the exit end of the press while the remaining portions of the uncompleted truss are being subjected to the press operation thus affording a savings in time and space. The foregoing is accomplished by a unique arrangement and mode of actuation of fluid actuated master and slave cylinders carried on the jig table. The leading heel pad on the jig table includes a member underlying the heel portion of the truss which member can be pivoted upwardly to elevate the completed leading heel portion of the truss from the jig table. A slave cylinder is connected to the pivoted member to effect the pivoting action thereof. A master cylinder is carried on the jig table rearwardly of the heel pad and is connected to the slave cylinder through a fluid line. A linkage connected to the master cylinder projects above both the jig table and the truss elements lying on the jig table. The press platen engages the linkage on its downward stroke when the nail plates of a succeeding joint are embedded, thereby actuating the master cylinder. Actuation of the master cylinder provides fluid to the slave cylinder which then pivots the hinged member upwardly thereby elevating the completed heel portion of the truss above the jig table surmounting the unloading device as the jig table emerges further from the press.

It is accordingly a primary object of the present invention to provide an improved unloading device for use with apparatus for manufacturing wooden structures.

It is another object of the present invention to provide an improved truss unloading apparatus including a truss elevating device which is automatically operable to elevate one end of the completed truss from a jig table.

It is still another object of the present invention to provide an improved truss unloading arrangement including a truss elevating device which is automatically reset for reuse.

It is a further object of the present invention to provide a truss unloading apparatus including a fluid actuated truss elevating device carried on the jig table and with minimum modification of the jig table.

It is still a further object of the present invention to provide a truss unloading apparatus for elevating one end of the completed truss in response to actuation of a truss fabricating press operating on remaining portions of the truss.

It is a related object of this invention to provide a truss unloading device which is automatic and simple in operation, economical to manufacture, readily and easily installed on existing jig tables, and does not require separate power sources.

These and further objects and advantages of the present invention will become more apparent upon reference to the following specification, claims and appended drawings.

DESCRIPTION OF THE DRAWING FIGURES

FIG. 1 is a fragmentary perspective view illustrating automatic machinery for fabricating trusses and shows the leading end of a truss elevated onto an unloading roller assembly by apparatus constructed in accordance with the present invention;

FIG. 2 is a fragmentary side elevational view of the truss elevating apparatus hereof;

FIG. 3 is a fragmentary side elevational view illustrating the leading end of a truss elevated onto a truss unloading apparatus by the elevating apparatus hereof;

FIG. 4 is a fragmentary plan view of the truss elevating apparatus hereof;

FIG. 5 is an enlarged plan view of the actuating assembly for the truss elevating device hereof with parts broken away for ease of illustration;

FIG. 6 is a cross sectional view thereof taken about on line 6—6 of FIG. 5;

FIG. 7 is a fragmentary end elevational view thereof taken about on line 7—7 of FIG. 4;

FIG. 8 is a fragmentary exploded perspective view of a hinged elevating assembly;

FIG. 9 is a plan view of the elevating assembly with parts broken away for ease of illustration; and

FIG. 10 is a side elevational view thereof illustrating the normal and truss raising positions of the truss elevating device hereof.

DESCRIPTION OF A PREFERRED EMBODIMENT

Referring to the drawings and more particularly to FIG. 1, there is shown an automatic system 10 for fabricating wooden structures, such as trusses. System 10 includes a conveyor, generally indicated at 12, on which jig assemblies 14 are carried. Conveyor 12 extends through a press 16 which may be of the type shown, for example, in assignee's U.S. Pat. No. 3,195,449. Press 16 is operative to press unitary connector plates 18 of the type illustrated, for example, in assignee's U.S. Pat. No. 2,877,523, into the structural butt joints as the latter are successively located below press 16 with jig assembly 14 being advanced along conveyor 12 from top to bottom as seen in FIG. 1. As will become clear, the apparatus of the present invention is effective to elevate the leading end of a completed truss 20 as it passes through the press and emerges therefrom on a truss unloading roller assembly, generally indicated at 22.

Unloading roller assembly 22 comprises longitudinally spaced transversely extending rollers 24 and 26 supported at the unloading side of system 10 in spaced relation above conveyor 12. Rollers 24 and 26 are supported above conveyor 12 such that truss 20 may be lifted from jig assembly 14 as the jig assembly is continuously advanced along conveyor 12. The opposite ends of rollers 24 and 26 are mounted in roller bearings 28 carried on stands 29 on opposite sides of conveyor 12. As seen more clearly in FIG. 3, a scoop plate 30, of generally triangular cross sectional configuration, is carried by stand 29 ahead of rollers 24 to guide truss 20 onto rollers 24 and 26.

The chords and web members which are joined together by the embedment of plates 18 at the joints thereof by press 16 to form a completed truss are manually positioned on jig assembly 14 and on opposite sides of the joints. Only the more significant details of jig assembly 14, which will be useful to bring out the environment of the present invention, are illustrated and reference is made to assignee's U.S. Pat. No. 3,241,585 for a more detailed description of the jig assembly and the working relationship of the elements thereof.

Briefly, jig assembly 14, seen in FIG. 1, is shown to be preset for production of a gable-type truss consisting of one or more bottom chords 30, top chords 32, and web members 34. Jig assembly 14 comprises a jig table, preferably formed of heavy sheet metal, upon which the

jig elements are mounted. A first pair of longitudinally extending stationary guide bars 38 and 40 are shown adjacent opposite sides of jig table 36 and a plurality of transversely extending guide bars 42 are longitudinally spaced along table 36. Bars 42 are provided with suitable connectors 44 at opposite ends which are slidable along longitudinally extending guide bars 38 and 40 whereby bars 42 may be selectively positioned along table 36. Reaction pad assemblies 46 are slidably mounted on transversely extending guide bars 42 whereby pads 46 may be selectively positioned transversely along jig table 36 below the butt joints formed by top chords 32 and webs 34.

Additional reaction pad assemblies 48 are selectively positioned along guide bars 38 below the butt joints formed by the ends of bottom chords 30 and the lower ends of upper chords 32. The arrangement and function of the reaction pads and guide bars are explained in detail in the aforementioned U.S. Pat. No. 3,241,584, it being sufficient for present purposes to refer only to the leading heel reaction pad assembly 50, i.e., the reaction pad which first enters into and emerges from press 16 and from which the heel portion of the truss will be initially elevated from jig table 36.

For background purposes, the jig is utilized by spotting connector plates 18 on each of the reaction pad assemblies with the teeth extending upwardly. The wooden chords and webs are then placed on top of the teeth and a second set of such connector plates are laid on top of the wooden chords and webs with their teeth directed downwardly, the reaction pad assemblies being located and providing releasable clamping devices for clamping the various members of the wooden structure in place to form a gable-type truss configuration. The jig table is then advanced through press 16 with the press being actuated when each of the butt joints underlies upper press platen 52 to simultaneously press the top and bottom connector plates 18 into the joints formed by the associated wooden members. As the truss structure emerges from press 16, it continues to lie on the reaction pad assembly and, since unloading rollers 24 and 26 are vertically spaced above the truss, table, and conveyor, the truss must be elevated from the jig table for positioning on unloading assembly 22. More particularly, the leading end of the truss is first elevated as to overlie scoop plate 30 and front roller 24 by the apparatus of the present invention with the remaining truss portions being progressively peeled from the reaction pad assemblies as the truss table and truss emerges from press 16 and are continuously advanced along conveyor 12.

Generally, the truss elevating apparatus hereof comprises a truss elevating control assembly, generally indicated at 53, and an elevating assembly, generally indicated at 54, responsive to actuation of control assembly 53 to elevate the leading end of the truss from the jig table 36 onto unloading assembly 22. The control assembly 53 includes a master cylinder which is actuated in response to downward movement of press platen 52 to actuate a slave cylinder carried by elevating assembly 54 which, in turn, pivots a member carried by heel reaction pad 50 and underlying the leading end of the truss to raise the truss from heel reaction pad 50.

More particularly, the elevating control assembly 53 comprises a base plate 56 having an upright flange 58 extending along one side thereof and mounting a pair of laterally spaced upstanding brackets 60 and 62 adjacent its opposite ends. A master cylinder 64 is pivotally mounted at one end to brackets 60 as by pin 66. Note that an elongated opening 67 is formed through base plate plate 56 and receives a body portion of cylinder 64 such that the vertical extent of plate 56 and cylinder 64 is limited for reasons as will become apparent. A piston rod 68 is carried by cylinder 64 and is biased outwardly by a spring 69. Piston rod 68 mounts a clevis 70 on its outer end to which the lower ends of a pair of links 72 and a roller 74 are connected as by a pin 76. The ends of links 72

lie on the opposite sides of clevis 70 with roller 74 lying between the legs of the clevis. The opposite ends of links 72 are pivotally connected to the upper end of link 78 as by a pin 80. A slot 82 is formed in the upper end of link 78 and a roller 84 is pivotally carried by pin 80 within slot 82. The lower end of link 78 is pivotally connected between brackets 62 as by a pin 86. The links 72 and 78 are formed such that roller 84 is normally spaced above the upper edge of flange 58 and cylinder 64 when piston rod 68 is fully extended under the bias of spring 69. In this manner, a downward force applied to roller 84 extends linkage 72 and 78 to the dashed line configuration in FIG. 6 to drive piston rod 68 toward a retracted position within cylinder 64 against the bias of spring 69 with roller 74 rolling along the upper face of base plate 56. Thus, fluid, preferably hydraulic fluid, will be forced from cylinder 64 through a nipple 88 and into a fluid line 90. When the force applied to roller 84 is removed, piston rod 68 will extend under the bias of spring 69 to relocate roller 84 in the normal vertically spaced position above the control assembly. That is, the linkage 72 and 78 and roller 84 move from the dashed line configuration to the full line configuration in FIG. 6.

For reasons described hereinafter, the elevating control assembly 53 is mounted on jig table 36 for selected longitudinal movement therealong. To this end, a longitudinally extending guide bearing member 91 is suitably secured to jig table 36 adjacent a lateral edge thereof and spaced outwardly of guide bar 38. A bracket 92, secured as by welding to base plate 56, projects laterally outwardly thereof to overlie bearing member 91 and carries a lug 94 on its underside adjacent its outer end. Bracket 92 is suitably apertured as at 96 and a locking screw 98 extends through aperture 96 in threaded engagement with a locking bar 100. Bearing member 91 and locking bar 100 have cooperating flanges 101 and 102, respectively, whereby threading and unthreading of screw 98 releasably clamps control assembly 53 in longitudinally adjusted position to and along bearing member 91.

Referring now to FIGS. 8-10, there is shown the elevating assembly 54 which comprises a hinged subassembly including a lever 103 hinged to the rear edge of heel reaction pad 50 as by an elongated pin 104. The hinged subassembly also includes a bar 106 suitably secured along the outer lateral edge of lever 103 and a roller surface or dowel 108 secured as by welding to the opposite free edge of lever 103. A bracket flat 110 is suitably secured to heel reaction pad 50 adjacent its forward lateral edge and a bracket 112 carrying a pair of upstanding flats 114 is suitably secured to flat 110 as by bolts 116. A fluid actuated slave cylinder 118 is pivotally mounted at one end to flats 114 as by a pin 120. A piston rod 122 is biased outwardly by a pin 124 and mounts a clevis 126 which is pivotally secured to a lever arm 128 as by a pin 130. Lever arm 128 is suitably hinged about pin 104 which projects beyond the lateral edge of heel pad 50. A hinge outboard bearing 132 is secured to the lateral edge of pad 50 adjacent its trailing end to receive the outer end of pin 104 and prevent lateral axial displacement of lever arm 128 along pin 104. As seen in FIG. 10, lever arm 128 underlies arm 106 such that clockwise pivoting of lever 128 about pin 104 pivots lever 103 in a like clockwise direction about pin 104. With lever 103 positioned adjacent the trailing edge of heel pad 50, it underlies the leading heel portion of the truss and it will be seen that retraction of piston rod 122 against the bias of spring 124 pivots lever arm 128 and lever 103 about pin 104 causing the heel portion of the truss to be elevated from heel reaction pad 50. Fluid line 90 is suitably connected to cylinder 118 to supply fluid thereto to retract piston rod 122 against the bias of spring 124. It will be noted that the clamps carried by the reaction pads to retain the chords and webs of the truss in place before table 36 passes through press 16 are automatically released as by operation of press platen 52 as noted in assignee's U.S. Pat. No.

3,238,867 and thereby the completed truss is free for elevating movement.

To manufacture a truss and position the same on unloading assembly 22 in accordance with the present invention, reaction pads 46 are selectively positioned along guide bars 42 with guide bars 42 being selectively positioned along guide bars 38 and 40. Reaction pads 48 are selectively longitudinally positioned along guide bars 38 such that the pads 46 and 48 underlie the joints of a specified truss. It will be noted that the only connection between control assembly 53 and elevating assembly 54 is fluid line 90 and that by unlocking control assembly 53 from bearing member 91, the elevating apparatus is free for longitudinal movement with heel reaction pad 50 along guide bar 38. When heel reaction pad 50 is properly positioned, control assembly 53 is located behind pad 50 along member 91, preferably in transverse alignment with one of the succeeding joints for reasons as will become apparent. Control assembly 23 is thus usually located about 8 feet behind pad 50, and is clamped in this position to member 91 and hence on jig table 36 behind leading reaction pad 50. The connector plates 18 are then spotted on the pads, as hereinbefore noted. The wooden members 30, 32 and 34 are arranged to form the truss 20, and the connector plates for the opposite side of the joints are spotted along the truss.

The truss manufacturing apparatus is actuated, by means not shown, to advance jig table 36, including the reaction pads, truss elements, connector plates, and the 30 truss elevating apparatus hereof, through press 16 to successively locate the joints of the press 20 below press platen 52. Press 16 is actuated, by means not shown, to drive press platen 52 downwardly to embed the plates 18 on opposite sides of the wooden members into the joints 35 formed thereby. It will be noted that the height of the control and elevating assemblies 53 and 54 does not exceed the combined height of the reaction pads and the truss members whereby assemblies 53 and 54 may pass below the press platen 52 when the latter is in its lowermost position and are not affected thereby.

As the leading portions of the completed truss and the 40 jig table emerge from the exit side of the press 16, the leading heel portion of truss 20 is elevated above heel reaction pad 50 as to overlie scoop plate 30 and front roller 24. To this end, the distance between the scoop plate 30 and the exit side of press 16 exceeds the distance between control assembly 53 and the leading edge of truss 20, whereby control assembly 53 is actuated to elevate the 45 leading truss portion before the leading edge of truss 20 passes below scoop plate 30. When control assembly 53 underlies press platen 52 and the latter is displaced downwardly to embed connector plates 18 into a joint, press platen 52 engages roller 84 causing linkage 72 and 78 to substantially straighten into the dashed line configuration 50 of FIG. 6, whereby piston rod 68 is driven against the bias of spring 69 in a direction to displace fluid from cylinder 64. The displaced fluid communicates into slave cylinder 18 via line 90 to retract piston rod 122. Retraction of rod 122 pivots lever arm 128 about pin 104 with lever arm 128 55 engaging the underside of arm 106 to pivot lever 103 about pin 104. As seen by the dashed lines in FIG. 10, this pivoting action of lever 103 causes dowel 108 to bear against and slide along the undersurface of the completed leading truss portion raising the latter from heel reaction pad 50 a distance such that the leading edge of truss 20 is elevated above scoop plate 30. Continuous advancement of jig table 36 along conveyor 12 brings truss 20 into overlying relation with rollers 24 and 26, whereby 60 truss 20 is stripped or peeled from successive reaction pads as it emerges from press 16.

Upon retraction of press platen 52, the springs 69 and 124 in cylinders 64 and 118, respectively, extend their associated piston rods whereby fluid communicates from slave cylinder 118 to master cylinder 64, returning fluid 65 to the master cylinder for subsequent operation. Note 70

that the pin 80 is offset above a straight line drawn between pins 76 and 86 when piston rod 68 is fully retracted. Accordingly, extension of piston rod 68 pivots linkage 72 and 78 to project roller 84 above control assembly 53 whereby the latter is ready for subsequent operation. The extension of piston rod 122 by spring 124 pivots lever arm 128 to its normal horizontal position. Lever 103, however, remains in the inclined position illustrated by the dashed lines in FIG. 10 with a stop 134 on a hinged portion of lever 103 precluding further clockwise pivotal movement from the dashed line position until arm 106 butts scoop plate 30, whereby arm 106 and lever 102 pivot back to the normal horizontal position with arm 106 directly overlying lever arm 128. Accordingly, after truss 20 is displaced from jig table 36 into overlying position on unloading rollers 24 and 26, the elevating device is automatically returned to its normal position ready for subsequent use.

The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. Apparatus for elevating at least a portion of a wooden structure formed of wooden elements connected one to the other by connector plates embedded into the joints thereof comprising means for supporting the wooden elements, a member carried by said support means in underlying relation to at least one of the wooden elements and mounted for pivotal movement, press means for embedding the connector plates into the joints, a fluid actuated cylinder operably connected to said member for pivoting said member from a first position to a second position elevating at least a portion of the structure above said structure means, and motor means spaced from said cylinder and operable in response to operation of said press means to actuate said cylinder and thereby pivot said member to said second position.

2. Apparatus according to claim 1 wherein said motor means comprises a second cylinder in fluid communication with said first mentioned cylinder and means connected to said second cylinder and responsive to operation of said press means to displace fluid from said second cylinder to said first cylinder.

3. Apparatus according to claim 1 wherein said support means includes a jig table, said member and said cylinder being carried by said jig table.

4. Apparatus according to claim 2 wherein said support means includes a jig table, said member and said cylinders being carried by said jig table.

5. Apparatus according to claim 4 wherein said cylinders and said member are mounted for longitudinal movement along said jig table, and means for clamping said cylinders and said member in adjusted longitudinal position along said jig table.

6. Apparatus according to claim 4 wherein said second cylinder connecting means includes a linkage carried by said jig table and projecting above the jig table and the wooden elements carried thereby, said press means including a reciprocable press platen, said linkage being operable to actuate the second cylinder in response to downward movement of said press platen toward the wooden elements.

5 7. Apparatus according to claim 6 wherein said second cylinder includes a piston rod, said linkage including a pair of links pivoted one to the other, an end of one of said links being pivotally carried by said jig table with the end of the other of said links pivotally connected to said piston rod, and a spring normally biasing said piston rod to a position projecting the common pivoted joint of said links above said jig table and the wooden elements.

10 8. Apparatus according to claim 5 including a heel reaction pad carried by said jig table for longitudinal movement therealong, said member being pivoted to said heel reaction pad and said first cylinder being carried by said heel reaction pad.

15 9. Apparatus according to claim 8 wherein said first cylinder has a piston rod, a lever arm connected to said piston rod and to said heel reaction pad, said lever arm underlying said member for joint pivotal movement with said member in one direction and independent pivotal movement in the other direction.

20 10. Apparatus according to claim 2 including an unloading assembly having a roller extending transversely across and spaced above said support means, said member elevating at least a portion of said structure onto said roller.

25 11. Apparatus for elevating a wooden structure formed of wooden elements connected one to the other by connector plates embedded into the joints thereof by a press comprising means for supporting the wooden elements 30 including a jig table longitudinally movable along a pre-determined path leading to and through the press, a member carried by said support means and mounted for movement between a first position and a second position elevating the structure above the support means, a pair of cylinders in fluid communication one with the other, one of said cylinders being coupled to said member for moving said member from said first position to said second position, the other of said cylinders being carried by said support means and longitudinally spaced from said first mentioned cylinder, said second cylinder being responsive to operation of the press to provide fluid to said first cylinder thereby to elevate the structure above said support means.

35 12. Apparatus according to claim 11 wherein said member and said cylinders are carried by said jig table for movement therewith.

40 13. Apparatus according to claim 11 wherein at least one of said cylinders is mounted for longitudinal movement along said support means, means for clamping said one cylinder to said support means in selective longitudinally spaced position from said other cylinder.

45 14. Apparatus according to claim 11 including linkage means connected to said other cylinder and projecting above said table and the wooden elements carried thereby, said linkage means being responsive to operation of the press to displace fluid from said other cylinder to said first cylinder.
